DESIGN FOR AIR CONDITIONING GAS FURNACE CABINET

Wilbur Henry Adams, Cleveland Heights, Ohio,
assignor to The Forest City Foundries Company,
Cleveland, Ohio, a corporation of Ohio

Application November 7, 1936, Serial No. 65,775

Term of patent 7 years

To all whom it may concern:

Be it known that I, Wilbur Henry Adams, a citizen of the United States and resident of Cleveland Heights, in the county of Cuyahoga and State of Ohio, have invented a new, original, and ornamental Design for an Air Conditioning Gas Furnace Cabinet, of which the following is a specification, reference being had to the accompanying drawing, forming a part thereof.

In said drawing, Fig. 1 is a front view of an air conditioning gas furnace cabinet showing my new design; Fig. 2 is a side view of such cabinet; Fig. 3 is a rear view of such cabinet; and Fig. 4 is a top plan view of such cabinet.

I claim:

The ornamental design for an air conditioning gas furnace cabinet, as shown.

WILBUR HENRY ADAMS.
